Filed Feb. 9, 1961, Ser. No. 88,200
8 Claims. (Cl. 340—167)

This invention relates to improvements in communication systems having multiple stations, and in particular relates to improved means for response by one station only to a signal meant only for that station.

By way of example, the invention can be applied to a radio telephony dialing system, wherein each station of the system will be responsive to a specific code number and to no other number.

One object of this invention is to provide means for detecting a selected number of pulses, without being responsive to a number of pulses which is either less than or greater than the selected number. Another important object of the invention is to provide a detector of this type which can be readily set for response to a differing number of pulses. Another object of the invention is to provide a detector or decoder which will respond to a series of signals, each containing a selected number of pulses.

By way of example, but without limitation thereto, a decimal numbering system may be employed. Thus, by way of example, if there are ninety-nine or fewer stations, each station may be responsive to a first number of pulses, corresponding to the tens digits, and then to a second number of pulses, corresponding to the ones digit. Thus, if some station first dials two pulses, and then dials four pulses, by way of example, as may be done on an ordinary telephone dial, the decoder at the station whose code number is twenty-four will automatically respond to first the two pulses and then, the four pulses and will produce an audible signal or other indication that the number twenty-four has been dialed.

As an important feature of the invention, the electric circuitry is relatively simple, and relatively minor modification is required for each additional digit which is to be dialed. Thus, by way of example, a seven digit number can be decoded, utilizing relatively simple circuitry.

As examples of other applications of the invention, it can be utilized to reduce the wiring in conventional telephone systems. Thus, only two wires would be needed in a telephone dialing system to carry the signal from one telephone set to all of the others.

Among other applications of this invention, the decoder may be used for selective paging systems, for selection of pulses to ring bells in various buildings, for selection of pulses in intercommunication systems, for selection of pulses in a fire alarm system or a call system, for an automatic combination lock system, for control of lighting systems, for general computer operations in counting of pulses and selection of desired pulses for digital computer systems.

In accordance with preferred embodiments of the invention, each station of a communication has an electric system for reception of input signals each comprising a varying number of electric pulses of relatively uniform duration and frequency which number may be less than, the same as or more than, a pre-selected number for which the system is set. This input signal may correspond to the pulses produced in ordinary telephone dial systems and may be supplied to the station by any suitable means.

Said station electric system has first circuit means receiving the input pulses and adapted to produce a first circuit output if and as soon as the number of pulses reaches the pre-selected number, or alternatively at the end of the time interval after the first pulse is received when the pre-selected pulse is due to be received. Said

2

station electric system has second circuit means also receiving the input pulses and adapted to produce a second circuit output at the conclusion of the pulses. Optionally, the second circuit means may not produce any output if the number of pulses received is less than the pre-selected number.

The system also includes output signal means coupled to the first and second circuits and adapted to produce an output signal when said first and second circuit outputs are in time co-incidence. If the received number of pulses is less than the pre-selected number, then either or both of said first and second circuit means produces no output at all; or if they both produce an output, the outputs are not in time co-incidence because the output of the first circuit means cannot occur before the conclusion of a time interval corresponding to the duration of the pre-selected number of pulses. If the received number of pulses is greater than the pre-selected number, then the outputs of the first and second circuit also cannot be in time co-incidence. The first and second circuit outputs can only be in time co-incidence when the system receives the pre-selected number of pulses.

As will be explained in detail in the specification, appropriate modification of the circuit may be incorporated in the event that the receiver is to respond to the dialing of two or more digital numbers.

Other objects and advantages of this invention will become apparent from the following description, in conjunction with the annexed drawing, in which preferred embodiments of the invention are disclosed.

In the drawing:

FIG. 1 is a block diagram of a first embodiment of the invention.

FIG. 2 is a detailed electric circuit diagram of the embodiment shown in FIG. 1.

FIGS. 3A, 3B and 3C are diagrammatic views showing the output wave forms of the various stages of the decoder, under illustrative conditions. The assumed illustrative conditions are that the decoder is set to respond to a two digit number, the first digit being 3. In FIG. 3A, it is illustratively assumed that the first digit actually dialed is less than three. In FIG. 3B, it is illustratively assumed that the first digit actually dialed is greater than three. In FIG. 3C, it is illustratively assumed that the first digit actually dialed is three, the decoder being thereby actuated so as to be in condition to be actuated by the correct dialing of the second digit.

FIG. 4 is a block diagram, also showing output wave forms, of the various stages of a second embodiment of the invention.

FIG. 5 is a block diagram, also showing output wave forms, of the various stages of a third embodiment of the invention.

FIG. 6 is a block diagram, also showing output wave forms, of the various stages of a fourth embodiment of the invention.

General Description of First Embodiment

FIG. 1 is a block diagram of a first embodiment of the invention. Illustratively, but without limitation thereto, FIG. 1 shows a two-stage decoder for decoding two digit numbers.

Stage 1 of the decoder, labeled "DIAL," represents a receiver for a series of pulses such as those produced on the ordinary telephone dial. Said stage one may include a source of such pulses, or may be a receiver for such pulses which are produced at a remote source and are transmitted by telephone or radio to said stage 1. The condition of the system is that said pulses of stage 1 be discrete, of relatively uniform amplitude, of relatively uniform duration in time and of relatively uniform fre-

quency. However, these conditions are not necessarily critical. Furthermore, if the received pulses differ too much in amplitude, for example, they may be clipped to uniform amplitude in stage 1.

Stage 1 is coupled by normally closed relay contacts K1 of relay K to integrator stage 2a, and by normally open relay contacts K2 of relay K to integrator stage 2b. Both integrator stages are coupled to stage 3, designated as the No. 1 one-shot multivibrator. When the first digit of the two digit number is being dialed, relay K is not energized and relay contacts K1 are closed. Integrator stage 2a is adjustable so that when the number of pulses equals or exceeds the selected first digit value, the output of stage 2a is sufficient to trigger stage 3 so that it produces an output pulse which is slightly longer in duration than the duration of an input pulse of the system. In the event that the number of pulses dialed is greater than the number selected for response by the decoder, so that the output of integrator 2 remains above the selected triggering level for a duration of more than one pulse, a pulse of longer time duration is produced by one-shot multivibrator 3.

The output of multivibrator stage 3 is divided and is fed respectively to a differentiator stage 4 and differentiator stage 5A. Optionally and preferably, said differentiators stages 4 and 5A are out of phase with each other. In other words, by way of example, differentiator 4 may produce a negative pulse corresponding to the beginning of the signal received thereby, and a positive pulse corresponding to the ending of the signal received thereby. Conversely, differentiator stage 5A may produce a positive pulse corresponding to the beginning of the input signal received thereby, and a negative pulse corresponding to the conclusion of the input signal received thereby.

The output of stage 4 is fed to stage 5, which is a No. 2 one-shot multivibrator stage. The negative differentiated output pulse of differentiator stage 4, corresponding to the beginning of the signal of stage 3, triggers a pulse output of one-shot multivibrator stage 5. The output pulse of one-shot multivibrator stage 5 is negative. This pulse is fed to the input of a back-biased diode stage 5B. The negative output pulse of differentiator 5A is also fed to the input of said stage 5B. If the pulses of stages 5 and 5A reach diode 5B at the same time, they are together sufficient in amplitude to overcome the back bias of diode 5B, and diode 5B produces a negative output pulse.

The negative output pulse of diode 5B is amplified by amplifier 6, and the output of amplifier 6 is fed through normally closed relay contacts K7 of relay K to stage 8, which is the first digit neon memory. Said first digit neon memory, stage 8, has a positive bias, for example of 105 volts, supplied thereto through line 32, and normally closed reset switch 31. Accordingly, stage 8 produces an output signal which is fed through amplifier 12 to relay K. Said neon memory 8 remains energized until reset switch 31 is opened.

The energization of relay K causes the relay contacts of stage 2 to be set for actuation of integrator stage 2b corresponding to the second digit, and similarly causes relay contacts K7 to be opened and relay contacts K9 to be closed.

Stages 1-6 operate as previously, for reception of the second set of pulses corresponding to the second digit, except that integrator stage 2b is set to cause response of stage 3 to the number of pulses corresponding to the second digit of the number. However, the output of amplifier 6 is in this case fed through relay contacts K9 to stage 10, which is the second digit neon memory. This memory is connected through line 33 and the aforesaid reset switch 31 to the source of positive voltage. The two neon memories operate in the same manner. The output of the second digit neon memory 10 is fed to a biased audio oscillator stage 11, which oscillator only operates to produce an output signal when it receives an input

signal from the stage 10. The output of stage 11 is fed to stage 13, which is a speaker or other appropriate signaling device.

If only a single digit response is required, amplifier 12, relay K, and integrator 2b and memory 10 may be omitted and memory 8 may be connected directly to oscillator 11.

Electric Circuit of First Embodiment

FIG. 2 shows an illustrative electric circuit for the embodiment shown in block diagram form in FIG. 1.

Stage 1 comprises switches 50 and 51 and associated elements. Switches 50 and 51 are switches of a telephone dialing system. Switch 50 is normally closed. When a number is dialed on the telephone dial, switch 50 is immediately opened and remains opened until the desired number is dialed. Thus, if the number 5 is dialed, the switch 50 will remain open for a duration of five pulses. Switch 51 is normally open and is closed and opened for each dialed pulse. For example, if the number 5 is dialed, switch 51 will close and then open again five times.

One side of switch 51 is connected to line 52, which in turn is connected to a source of $-22\frac{1}{2}$ v. The other side of switch 51 is connected through adjustable resistors 54 and 55 and switch 50 in series to line 53 which is grounded. Relay contacts K2 are connected across resistor 54. Relay contacts K1 are connected across resistor 55. Resistor 56 and condenser 57 are connected across switch 50. The cathode of diode 58 is connected to the junction of resistor 55 with switch 50, resistor 56 and condenser 57. The plate of diode 58 is connected to the base of PNP transistor 59.

Resistor 54 and resistor 56 and condenser 57 serve as integrator stage 2. Resistor 55 and resistor 56 and condenser 57 serve as integrator stage 2b.

When relay contacts K1 are closed, the dialing of a number causes a series of pulses (depending on the number dialed) to travel from the $-22\frac{1}{2}$ v. source through line 52, switch 51, resistor 54 and resistor 56 and condenser 57 in parallel (switch 50 being open) to ground. The voltage built up across condenser 57 depends upon the setting of resistor 54. At the conclusion of the pulses, switch 50 closes, and condenser 57 is shorted. However, prior to the closing of switch 50, the voltage across condenser 57 applied to the cathode of diode 58 causes current to flow to the base of transistor 59.

The operation when contacts K2 are closed does not require extended description.

Transistor 59 and the further PNP transistor 60 (all transistors in the circuit are PNP transistors), with associated circuitry, serves as the No. 1 one-shot multivibrator stage 3. The emitters of transistors 59 and 60 are connected together. The collectors of transistors 59 and 60 are respectively connected by resistors 59a and 60a to line 52. The collector of transistor 59 is connected by condenser 62 to the base of transistor 60. The collector of transistor 60 is connected by condenser 63 to the cathode of diode 65 and also to resistor 64 which is in turn connected to grounded line 53. The base of transistor 60 is connected by resistor 60b to voltage line 52.

Condenser 63 and resistor 64 together serve as differentiator stage 4. The resistance between base and collector of transistor 59, together with condenser 61 which is connected between the collector of transistor 59 and the cathode of diode 5B, together serve as differentiator stage 5A.

The plate of diode 65 is connected by resistor 65a to grounded line 53 and is also connected to the base of transistor 66. Transistors 66 and 67, with associated circuitry, serve as No. 2 one-shot multivibrator stage 5. The collectors of transistors 66 and 67 are respectively connected by resistors 66a and 67a to voltage line 52. The emitters of transistors 66 and 65 are connected by resistor 66b to grounded line 53. The emitter of transistor 66 is connected by condenser 66c to the base of

transistor 67. The base of transistor 67 is also connected by resistor 67b to voltage line 52. The collector of transistor 67 is connected to the cathode of diode 5B.

If the negative voltage on the cathode of diode 5B becomes sufficiently great, transistor 59 conducts current between its collector and plate. The signal is differentiated by condenser 61, and at its conclusion a negative pulse is supplied to the cathode of diode 5B.

When transistor 59 conducts current, transistor 60 conducts less current, causing a negative pulse to be supplied to condenser 63. As a result, the cathode of diode 65 becomes more negative, and transistors 66 and 67 are operative to supply a negative pulse to the cathode of diode 5B.

Ordinarily, the cathode of diode 5B is not sufficiently negative with respect to the plate for it to conduct a sufficient amount of current to actuate subsequent stages of the circuit. If a negative signal through condenser 61 and a further negative signal from the collector of transistor 67 are supplied to the cathode of diode 5B, it conducts a substantial amount of current which is supplied to the amplifier stage 6 consisting of transistors 68 and 69 and associated circuitry.

The plate of diode 5B is connected to the junction between resistor 68a and condenser 68b. Resistor 68a is further connected to voltage line 52. Condenser 68b is connected to the base of transistor 68. Base 68 is connected by resistor 68c to grounded line 53. The emitters of transistors 68 and 69 are connected to grounded line 53. The collectors of transistors 68 and 69 are respectively connected by resistor 68d and resistor 69d to voltage line 52. The collector of transistor 68 is connected by condenser 69a to the base of transistor 69. The base of transistor 69 is connected by resistor 69b to voltage line 52.

Line 52 is connected by resistor 52a to ground. +105 v. source is connected by normally closed reset switch 31 and resistors 72 and 73 in series to ground, and also by switch 31 and resistors 72a and 73a in series to ground. The collector of transistor 69 is connected through condenser 70 and normally closed relay contacts K7 to a first side of first digit neon memory 8, the other side of which is connected to the junction between resistors 72 and 73. The collector of transistor 69 is also connected through condenser 70 and normally open relay contacts K9 to a first side of second digit neon memory 10, the other side of which is connected to the junction between resistors 72a and 73a. Said first sides of memories 8 and 10 are respectively connected through resistors 75 and 74, on the one hand, and 75a and 74a, on the other hand, to ground line 53. Resistor 74b and condenser 74c are connected in parallel across resistor 74a.

The junction of resistors 74 and 75 is connected by line 76 to the base of transistor 77. Transistors 77 and 78, with associated circuitry, together serve as amplifier stage 12. The bases of transistors 77 and 78 are respectively connected by resistors 77a and 78a to line 52b which is connected to -22½ v. source. The emitters of transistors 77 and 78 are connected to line 53a which is grounded. The collector of transistor 77 is connected to the base of transistor 78. The collector of transistor 78 is connected by relay coil K to voltage line 52b. Resistor 78c is connected between lines 52b and 53a.

The junction of resistors 74a and 75a is connected by line 79, to the emitters of transistors 80 and 81, which, together with associated circuitry, serve as audio oscillator stage 11. The bases of transistors 80 and 81 are respectively connected by resistors 80a and 81a to grounded line 53a. The base of transistor 80 is connected by condenser 80b to the collector of transistor 81. The base of transistor 81 is connected by condenser 81b to the collector of transistor 80. The collector of transistor 80 is connected by resistor 80c to voltage line 52b. The collector of transistor 81 is connected by resistor 82 and audio transformer primary 83 to voltage

line 52b. The secondary 84 of the audio transformer is connected across voice coil 13a of speaker 13.

When diode 5B receives two signals in time coincidence, its cathode becomes sufficiently negative relative to its plate so that it passes a signal to amplifier stage 6. The transistors 68 and 69 of stage 6 amplify this signal, and an output signal through relay contacts K7 causes the adjacent side of memory 8 to become more negative. The voltage drop across memory 8 is then sufficiently great so that the tube fires.

As the result of the firing of tube 8, a positive voltage drop across resistor 74 is applied to the bases of transistor 77 of amplifier stage 8. The amplified signal of transistors 77 and 78, through relay coil K, energizes the relay, causing contacts K2 and K9 to close and K1 and K7 to open.

When the next series of pulses is received, if the number corresponds to the pre-set value (adjustment of resistor 55), diode 5B again receives two pulses in time coincidence, and memory 10 fires. The positive voltage drop across resistor 74a is fed to the base of transistor 89 of audio oscillator stage 11. Oscillator stage 11 is thereby triggered to produce an audio frequency signal which is applied to transformer 83, 84 and hence to speaker 13 to produce an audible signal.

Summary of Operation

FIGS. 3A, 3B and 3C show diagrammatically the wave forms corresponding to illustrative conditions of operation of the decoder. It is illustratively assumed that the first digit integrator stage 2a is set for response to the dialing of three pulses. It is further assumed that this is a two digit dialing system, corresponding to the assumed illustrative condition of FIG. 1.

FIG. 3A shows the condition for the dialing of a first digit of two pulses. The reference numerals under the wave form diagram of each of the views correspond to the reference numeral of the corresponding stage shown in the block diagram of FIG. 1. Thus, the Diagram 1 in FIG. 3A shows two pulses numbered 1 and 2, corresponding to the dialing of two pulses in stage 1. Diagram 2 shows the corresponding output of integrator stage 2a, showing this output to be below the trigger level (broken lines) which is required to energize one-shot multivibrator stage 3. Since one-shot multivibrator stage 3 is not actuated, there are no further signals produced by any of the stages of the decoder.

In FIG. 3B, it is illustratively assumed that the first digit number dialed has been 4, or one greater than the pre-set number for response. Diagram 1 of FIG. 3B corresponds to the dialing of four pulses in stage 1.

As shown in Diagram 2a of FIG. 3B, the output of integrator stage 2a is now greater than the trigger level necessary to actuate stage 3. Furthermore, as shown in Diagram 3 of FIG. 3B, since integrator 2a is actuated above the trigger level for a time corresponding to two dial pulses, one-shot multivibrator stage 3 has a negative output of duration equal to the duration of two pulses of stage 1.

Diagram 4 of FIG. 3B shows the resulting differentiated output waveform of differentiator stage 4. This has a negative beginning pulse and a positive concluding pulse.

Diagram 5 of FIG. 3B shows the resulting negative output signal of No. 2 one-shot multivibrator stage 5, (slightly longer than the duration of one pulse of stage 1), actuated by the negative initial pulse of differentiator stage 4. Diagram 5A of FIG. 3B shows the differentiated output signal of stage 5A, having a positive beginning pulse and a negative concluding pulse, this negative concluding pulse corresponding in time substantially to the conclusion of the fourth pulse of stage 1. Since the conclusion of the pulse of stage 5 is prior in time to the conclusion of pulse 4 of stage 1, the output pulses of stages 5 and 5A are not in time co-incidence. Since

the amplitude of each pulse by itself is insufficient to overcome the back bias of diode 5B, amplifier 6 does not receive an input signal and consequently produces no output signal. Accordingly, stage 8 receives no signal and relay K remains unenergized. Hence, the decoder does not respond to the dialed number 4.

In FIG. 3C, it is assumed that the correct digit 3 has been dialed, as shown by Diagram 1. Accordingly, as shown in Diagram 2a of FIG. 3C, the integrator output (stage 2a) is sufficient in amplitude and in duration to trigger only a single negative output pulse of one-shot multivibrator stage 3. The differentiated output (Diagram 4 of FIG. 3B) of stage 3 produces a negative output pulse of stage 5 which lasts a time interval slightly greater than the time interval corresponding to one pulse in stage 1, but less than the time interval corresponding to two such pulses.

The differentiated output signal of stage 5a (Diagram 5a of FIG. 3C) has its negative pulse at a time corresponding to the conclusion of the third pulse of stage 1. Accordingly, the output of stages 5 and 5A are in time co-incidence, resulting in a negative output pulse of stage 5b. As shown in diagram 6, this negative pulse is amplified by amplifier stage 6 and is fed through relay contacts K7 to the first digit neon memory stage 8. Diagram 8 of FIG. 3 shows the resulting D.C. voltage step of stage 8. Diagram 12 of FIG. 3C shows the resulting D.C. current step produced by amplifier 12, which energizes relay K.

It will be apparent, without extended showing, that similar type wave forms will be produced when the second digit is dialed, and if the second digit is properly dialed, a positive D.C. voltage will be produced in stage 10, similar to that shown in stage 8 in FIG. 3. As stated above, this will result in the production of a signal of stage 11 and corresponding audible signal in stage 13.

When switch 31 is momentarily opened, as by the operator of the station picking up the receiver in response to the audible signal of stage 13, the D.C. voltage output of stages 8 and 10 will be eliminated, and the audible signal will stop. Switch 31 may then be again closed, so that the decoder will be reset for reception of the next signal.

In summary, in the first embodiment, stage 1 receives input signals each comprising a varying number of electric pulses of relatively uniform duration and frequency which number may be less than, the same as or more than a pre-selected number. Integrator stage 2a, No. 1 one-shot multivibrator stage 3 and differentiator stage 5A serve as first circuit means receiving the pulses and adapted to produce a first circuit output when the number of pulses reaches the preselected number. Integrator stage 2a, No. 1 one-shot multivibrator stage 3, differentiator stage 4 and No. 2 one-shot multivibrator stage 5 serve as second circuit means receiving the pulses and adapted to produce a second circuit output at the conclusion of pulses at best equalling the pre-selected number of pulses. "AND" gate diode 5B, amplifier 6 and memory tube 8 serve as output signal means coupled to said first and second circuit means for reception of the outputs thereof and adapted to produce an output signal when said first and second circuit outputs are in time co-incidence.

Embodiment of FIG. 4

The block diagram of FIG. 4 shows a circuit set to respond to a single digit input of time duration T_a , illustratively assumed to be the time of four pulses. It is assumed that the input signal is in fact four pulses.

FIG. 4 shows a dial stage 21, similar to dial stage 1 of FIG. 1, and shows diagrammatically the resulting pulse wave form of said dial stage 21 (assuming that four pulses of time duration T_a are dialed). Stage 22 is a slowing circuit which produces an output pulse corresponding in duration (time T_a) to the number of pulses of stage 21,

but of uniform wave form. The output of stage 22 is fed in part to integrator stage 23 and in part to differentiator stage 25. At time T_a , the output of integrator stage 23 reaches the pre-set level sufficient to fire pulse generator stage 24. Accordingly, at the conclusion of the time T_a , pulse generator stage 24 produces a positive pulse. Differentiator stage 25 produces a negative output pulse at the conclusion of the signals supplied to differentiator stage 25 (time T_a). Said negative pulse and the output of pulse generator 24 are compared in "AND" stage circuit 26.

The signal of the pulse generator 24 takes place as soon as the number of pulses reaches the number for which integrator 23 is pre-set. Accordingly, if the negative pulse output of differentiator 25 takes place at that time, the "AND" circuit 26 is actuated and produces an output. On the other hand, if the number of pulses of stage 21 exceeds the pre-set number, then the time of the negative pulse of differentiator 25 is after the pulse of generator 24, and "AND" circuit 26 is not energized.

In this embodiment, showing stage 22, integrator stage 23 and pulse generator stage 24 serve as the first circuit means and produce a first circuit output when the number of pulses reaches the pre-selected number. Stage 22 and differentiator stage 23 serve as the second circuit means and produce a second circuit output at the conclusion of the pulses. "AND" circuit 26 produces an output signal when the first and second circuit outputs are in time co-incidence.

Embodiment of FIG. 5

In this embodiment, stages 21, 22 and 25 are also employed. However, instead of integrator 23 and pulse generator 24, there are employed a saw-toothed oscillator or pulse generator 49, for reception of part of the signal of stage 22, and a clipper 41 for reception of the output of stage 40. Stage 40 produces output corresponding to the input signal received from stage 22. If the output of stage 40 reaches the pre-set level, a signal is provided which is sufficient to actuate clipper stage 41, which thereby produces an output signal corresponding to the time incidence of the pulse for which the decoder is set for response. In the meantime, as in the embodiment of FIG. 4, differentiator 25 produces a negative pulse corresponding to the conclusion of the actual number of pulses of stage 21. In other words, the negative pulse of differentiator 25 may take place before, at the same time as or after the time interval corresponding to the number of pulses for which the decoder is pre-set, depending upon whether the number of pulses of stage 21 is less than, the same as or more than the pre-set number. In any event, the output of stage 25 and the output of stage 41, which are together fed to "AND" circuit stage 42, only energize this stage 42 to produce an output if they are in time unison.

Embodiment of FIG. 6

Illustratively, a two-digit system is shown, with relays eliminated and with recycling means provided to re-set the system within a selected time after the first number is dialed.

For convenience of illustration, stages 21 and 22 are not shown. In any event, a signal of time duration T_a , corresponding to the time T_a of the input pulses, is shown as being fed to differentiator stage 90. This stage produces a positive pulse at time T_0 (the start of the pulses) and a negative pulse at time T_a (the end of the pulses).

The positive pulse of differentiator stage 90 supplied to controlled one-shot multivibrator No. 1 stage 91 causes it to produce a negative output pulse of time equal to the duration of the pre-selected number of pulses. The duration of the pulse of stage 91 is controlled by regulation of its R-C circuit. The output of stages 91 goes to differentiator stage 92 which produces a positive pulse at the end of the time duration of the desired or

pre-selected number of pulses. The output of stage 92 goes to one-shot multivibrator stage 93 which produces a negative pulse as the result of the positive pulse of stage 92, of time duration equal to the time duration of one pulse.

The pulse of stage 93 goes to "AND" gate stage 94. The negative pulse of differentiator 98, corresponding to the conclusion of the input pulses, is also supplied to stage 94. If the two signals supplied to gate 94 are in time co-incidence, it produces an output.

Accordingly, in this embodiment, the first circuit means comprising stages 90, 91 92 and 93 produce a first circuit output at the end of the time interval after reception of the first pulse when the pre-selected pulse is due to be received. Stage 90 serves as the second circuit means producing a second circuit output at the conclusion of the pulses.

The output of gate 94 is supplied to the set input terminal S of flip-flop circuit 95. This has two output terminals 95a and 95b. Normally, the output at terminal 95a is high and at 95b low, this condition being reversed when the flip-flop is "fired." The signal from gate 94 fires flip-flop 95.

Terminal 95a is coupled to controlled one-shot multivibrator No. 1 stage 91. Terminal 95b is coupled to controlled one-shot multivibrator No. 2 stage 91a. When terminal 95a is "high" and 95b "low," stage 91 can produce an output and 91a cannot. When terminal 95b is "high" and 95a "low," stage 91a can produce an output and 91 cannot.

Terminal 95b is coupled to the following successive recycling stages: differentiator stage 96, univibrator stage 97, differentiator stage 98 and amplifier stage 99. When flip-flop 95 is "fired" so that terminal 95b becomes "high," a positive step function is applied to differentiator 96. This produces a negative pulse which causes stage 97 to fire, this being a one-shot multivibrator that generates a pulse of 4-6 seconds duration. At the end of that time, the negative output pulse of differentiator 96 causes amplifier 99 to produce an output which is supplied to recycling input terminal R of flip-flop 95. If the proper second digit has not yet been dialed, flip-flop 95 is reset to its initial position, so that stage 91 can again be active if the proper first digit is dialed.

If during the 4-6 second interval before recycling, a second signal is received, the positive output pulse of stage 90 is supplied to stage 91a (which is also coupled thereto) and causes it to produce an output of time duration equal to the duration of the pre-selected number of second digit pulses. The output of stage 91a is supplied to differentiator 92. Accordingly, if the correct second digit number is dialed, gate 94 again receives two input signals in time co-incidence and produces an output signal.

The output of gate 94 this time produces no effect on flip-flop 95 which has already been fired. However, terminal 95b of flip-flop 95 and gate 94 are both coupled to "AND" circuit stage. When terminal 95b is "high" and when gate 94 produces a signal, stage 100 produces an output. This is amplified by amplifier stage 101, which thereby fires audio oscillator stage 102, which in turn drives speaker 103 to produce an audible signal. Oscillator 102 can be set to operate for a selected time interval.

While preferred embodiments of the invention have been disclosed, and various possible changes, omissions and additions have been indicated therein, it will be apparent that various other changes, omissions and additions may be made in the invention without departing from the scope and spirit thereof.

Thus, each of the circuits shown may be readily modified to accommodate a dialing system having one, two, three or more digits. Instead of discreet input pulses, there may be an input signal of varying duration which is an integral multiple of a basic time unit. The various stages of each embodiment may comprise various known circuit components. Other modifications are possible.

What is claimed is:

1. In an intercommunication system having a plurality of stations, an electric signaling system comprising operator-controlled means at each station for transmitting simultaneously to all other stations an operator-selected number of electric signal pulses of relatively uniform duration and frequency, and means at each station receiving all signal pulses of the system and automatically responsive to a pre-selected number, distinctive for each station, of said pulses, whereby an operator at one station can call another station by transmitting the number of pulses distinctive for such other station, said pulse-receiving and responsive means comprising first circuit means receiving said pulses and responsive to said pulses to produce a first circuit output corresponding to the conclusion of the time interval required for reception of the pre-selected number of pulses, second circuit means receiving said pulses and responsive to said pulses to produce a second circuit output at the conclusion of the actual pulses received, and output signal means coupled to said first and second circuit means for reception of the outputs thereof and responsive thereto to produce an output signal when said first and second circuit outputs are in time coincidence.

2. An electric signaling system in accordance with claim 1, said first circuit means producing said first circuit output when the number of pulses reaches the pre-selected number, said second circuit means producing said second circuit output at the conclusion of pulses at least equaling the pre-selected number of pulses.

3. Electric signaling system according to claim 1, said first circuit means comprising a signal integrator, a first one-shot multivibrator coupled to said integrator and producing pulses corresponding to input pulses starting with when the number of input pulses reaches the pre-selected number, a first differentiator coupled to said first one-shot multivibrator and producing an output pulse corresponding to the beginning of the pulses of said first one-shot multivibrator, said second circuit means comprising said integrator and said first one-shot multivibrator and also comprising a second signal differentiator coupled to said first one-shot multivibrator and producing a pulse corresponding to the conclusion of the pulses of said first one-shot multivibrator, and a second one-shot multivibrator coupled to said second differentiator and producing a pulse in response to the pulse of said second differentiator.

4. Electric signaling system according to claim 1, said first circuit means producing said first circuit output when the number of pulses reaches the pre-selected number, said second circuit producing said second circuit output at the conclusion of the pulses.

5. Electric signaling system according to claim 4, said first circuit means comprising a slowing circuit producing a signal of relatively uniform amplitude and of time duration corresponding to the total time duration of the input pulses, a signal integrator coupled to said slowing circuit, and a pulse generator coupled to said integrator and producing a pulse when the output of said integrator reaches a pre-selected value corresponding to the pre-selected number of pulses, said second circuit means comprising said slowing circuit and a differentiator coupled to said slowing circuit, said differentiator producing an output pulse corresponding to the conclusion of the signal of said slowing circuit.

6. Electric signaling system in accordance with claim 4, said first circuit means comprising a slowing circuit producing a signal of relatively uniform amplitude and of time duration corresponding to the time duration of the input pulses, a generator coupled to said slowing circuit and producing an output signal of amplitude in proportion to the duration of the input pulses, and a clipper coupled to said generator and producing a signal when the output of said generator reaches a value corresponding to the reception of the pre-selected number of pulses, said second circuit means comprising said slowing circuit and a differentiator coupled to said slowing circuit and producing an

output signal corresponding to the conclusion of said slowing circuit.

7. Electric signaling system according to claim 1, said first circuit means producing a first circuit output at the end of the time interval after reception of the first pulse when the pre-selected pulse is due to be received, said second circuit means producing said second circuit output at the conclusion of the pulses.

8. Electric signaling system in accordance with claim 7, said first circuit means comprising a slowing circuit producing an output signal of relatively uniform amplitude and of time duration corresponding to the duration of the input pulses, a first differentiator coupled to said slowing circuit and producing an output pulse corresponding to the beginning in time of the input of said first differentiator, a first one-shot multivibrator coupled to said first differentiator and producing a signal of time duration corresponding to the duration of the pre-selected number of pulses, a second differentiator coupled to said first one-shot multivibrator and producing a signal corresponding to the conclusion of the signal of said first one-shot multi-
